CONTROLLER FOR MODEL RACING CARS OR SIMILAR ARTICLE

Henry S. Rose, Los Angeles, and James B. Russell, Altadena, Calif., assignors to American Russkit Company, Los Angeles, Calif., a corporation of California

Filed June 12, 1964, Ser. No. 80,378

Term of patent 14 years

(Cl. D52—6)

FIGURE 1 is a perspective view of a controller for model racing cars or similar article, showing our new design;

FIGURE 2 is a side elevational view; and

FIGURE 3 is an end elevational view.

The undisclosed side of the controller is the same in appearance as the side shown.

We claim:

The ornamental design for a controller for model racing cars or similar article, substantially as shown and described.
